UNITED STATES PATENT OFFICE.

MARY PRUGH, OF LOS ANGELES, CALIFORNIA.

DESIGN FOR A CHRISTMAS BAG OR PACK.

No. 39,516.

Specification for Design.

Patented Sept. 8, 1908.

Application filed June 16, 1908. Serial No. 438,866. Term of patent 14 years.

To all whom it may concern:

Be it known that I, MARY PRUGH, a citizen of the United States, residing at Los Angeles, in the county of Los Angeles, State of California, have invented a new, original, and ornamental Design for Christmas Bags or Packs, of which the following is a specification, reference being had to the accompanying drawing, forming part hereof.

Figure 1 is a plan view of the obverse or face of the bag or pack showing my new design; and Fig. 2 is a similar view of the reverse or rear side of the same.

I claim:

The ornamental design for a Christmas bag or pack, as shown.

MARY PRUGH
